UNITED STATES PATENT OFFICE

142,176

DESIGN FOR A PLAYING CARD HOLDER OR SIMILAR ARTICLE

Luis Tacón and Armand L. Cueva,
New York, N. Y.

Application May 15, 1944, Serial No. 113,588

Term of patent 14 years

(Cl. D34—13)

To all whom it may concern:

Be it known that we, Luis Tacón and Armand L. Cueva, a citizen of Cuba and a citizen of the United States, respectively, residing at New York, in the county of New York and State of New York, have invented a new, original, and ornamental Design for a Playing Card Holder or Similar Article, of which the following is a specification, reference being had to the accompanying drawing, forming part thereof.

Fig. 1 is a top perspective view of a playing card holder, showing our new design, and Fig. 2 is a side elevation thereof.

We claim:

The ornamental design for a playing card holder or similar article, as shown.

LUIS TACÓN.
ARMAND L. CUEVA.
